UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 923,503.

Specification of Letters Patent.

Patented June 1, 1909.

Application filed January 21, 1909. Serial No. 473,440.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

My invention relates especially to retard-
ing contrivances for typewriting machines,
and has for its main object to provide im-
proved devices of this description.

To the above and other ends, the inven-
tion consists in the features of construction,
combinations of devices and arrangements of
parts hereinafter described, and particularly
pointed out in the claims.

My invention is shown as applied to a
Monarch typewriting machine, but the na-
ture of said invention is such that it may be
adapted to other styles of writing machines.
This invention has been made as an im-
provement on the construction shown in my
Letters Patent No. 898,635 dated Sept. 18,
1908 and also as an improvement on the con-
struction devised by Herbert H. Steele and
set forth in his pending application for patent
Sr. No. 471,627 filed Jan. 11, 1909.

In the drawings, Figure 1 is a vertical front
to rear sectional view of a Monarch typewriting
machine embodying my invention, parts
of the machine being omitted. Fig. 2 is a
fragmentary vertical sectional view showing
details of the escapement devices. Fig. 3 is
a rear elevation of the machine, parts being
omitted and parts broken away. Fig. 4 is a
rear elevation, partly in section, showing on
an enlarged scale the retarding contrivance
and associate parts, the cover plate of said
contrivance being omitted. Fig. 5 is a hori-
zontal sectional view of the retarding con-
trivance taken on a plane represented by the
dotted line *x* in Fig. 4 and looking in the di-
rection of the arrow at said line, the cover
plate, the escapement wheel and pinion and
the supporting bracket therefor also being
shown. Fig. 6 is a front elevation showing
the retarding contrivance and associate
parts. Fig. 7 is a perspective view of a part
comprised in the retarder contrivance. Fig.
8 is a perspective view showing a modifica-
tion of one of the retarding elements.
Figs. 9, 10 and 11 are respectively longitudi-
nal vertical, transverse vertical, and hori-
zontal sectional views illustrating a modified

spring adjusting device for the retarder con-
trivance. Figs. 12, 13 and 14 are respec-
tively a vertical section, front elevation, and
top plan views illustrating my preferred con-
struction and arrangement.

Referring especially to Figs. 1 to 3 of the
drawings, the main frame of the machine is
shown as comprising a base 1, corner posts 2
and a top plate 3. The usual printing in-
strumentalities (not shown) are mounted on
the main frame and are adapted to coöperate
with the front face of a platen 4 mounted in a
carriage composed of end bars 5 and a con-
necting rear or slide bar 6. The slide bar is
grooved at its top and bottom faces to co-
operate with bearing balls 7 which also co-
operate with grooved guide rails 8 secured
to fixed standards 9. Arms 10 pivoted on
the end bars of the carriage, support a spring-
pressed feed rack 11 which normally meshes
with a feed pinion 12 fixed to the front end of
a horizontal shaft 13 bearing in a bracket 14
secured to the top plate. An escapement
wheel 15 is supported at the rear end of the
shaft 13 and is operatively connected there-
with, said escapement wheel coöperating
with feed dogs 16 and 17 mounted at the top
of a dog rocker 18, said dog rocker being
pivoted at 19 on a bracket 20 depending
from the top plate. A link 21 connects the
dog rocker with a universal bar (not shown)
which is operated by the key levers in the
customary way. A spring drum 22 is con-
nected by a strap 23 with a pin 24 depending
from the carriage. Said spring drum, as is
well known, contains a main spring which
tends constantly to draw the carriage left-
ward over the top plate, the carriage move-
ments in this direction, however, being ordi-
narily controlled by the operation of the es-
capement devices during the printing or
spacing of the different characters in a line of
writing.

The drawings illustrate tabulating mech-
anism which comprises a stop arm 25 secured
by screws 26 to the slide bar 6. The stop 25
projects rearwardly from the slide bar and is
adapted to coöperate with one or more tabu-
lator stops 27 adjustably mounted on a
toothed stop bar 28, said stop bar being jour-
naled on arms 9^a extending rearward from
the standards 9. The stops 27 are normally
above the stop 25, as shown in Fig. 1, but the
stop bar 28 is adapted to be turned in its
bearings to bring said stops in a line so that

they may coöperate when the carriage is released. The means for thus turning the stop bar 28 comprise an arm 29 secured at the right-hand end of the bar 28, said arm being 5 pivotally secured to a downwardly extending link 30 which passes through an opening in the top plate and is pivotally connected at its lower end with one arm of a bell crank lever 31, said bell crank being fulcrumed at 10 32 to a fixed bracket 33. The other arm of said bell crank is pivotally connected with a forwardly extending slide rod 34 which passes through and bears in an opening in the right-hand front corner post 2, said slide rod 15 at its front end being provided with a tabulator key or button 35. A spring 36 coiled around the upper portion of the link 30 operates to maintain the stop bar 28 and its actuating devices in normal position. When the 20 tabulator key 35 is pushed in, it operates through the rod 34 and bell crank 31 to pull the link 30 downward against the tension of the spring 36 and turn the stop bar 28 so as to bring the stops 27 thereon into line with 25 the tabulator stop 25 on the carriage. Concurrently the carriage is released.

The means for releasing the carriage which are operated by the tabulator key 25 comprise a finger 37 fixed to and projecting from 30 the link 30 and contactive with one arm of a lever 38 pivoted at 39 on a fixed lug 40. The other arm of the lever 38 is pivotally connected at 41 with a lifting device 42, said device being bifurcated at its upper portion to 35 engage with cut-outs in the sides of the bracket 14. As usually constructed the bifurcations at the upper end of the device 42 terminate in lifting shoes which are adapted to engage with the teeth of the rack 11 to 40 separate it from the feed pinion 12 and release the carriage. In the present case, however, I prefer to dispense with these lifting shoes and in the form now being described to provide the device 24 with a lateral off-set 45 42^a formed with a horizontal slot 42^b which provides a connection to the retarding contrivance, operating said contrivance to release the carriage as hereinafter described.

The retarding contrivance is pivotally supported on a bracket composed of two right-angled plates 43 and 44, the plate 44 having a horizontal arm which rests on a corresponding horizontal arm of the plate 43, the two plates being secured to the top plate 3 by a 50 headed screw 45. Ears 43^a on the bracket plate 43 prevent relative motion between said plate and the plate 44. A pin or dowel 46 passes through the horizontal portions of the two plates into the top plate and prevents 55 the bracket as a whole from turning on the screw 45 as a pivot. The upstanding arms of the plates 43 and 44 are spaced apart to receive between them the retarding contrivance which is pivotally mounted on a headed screw 60 and shouldered screw 47. Said screw, as

best shown in Fig. 5, engages openings in said upstanding arms, the smaller opening which is in the plate 44 being tapped to receive the reduced and threaded end portion of the screw 47. The retarding devices are contained in a casing which consists of a box-like part or container 48 and a cover plate 49 therefor. The engaging edges of the box 48 are provided with lugs 48^a which fit into corresponding notches in the cover plate 49 75 providing a dove-tail construction which prevents slipping between the two parts. Before the cover plate 49 is fitted on and the case mounted on the pivot screw 47, the retarding devices proper are arranged within 80 the box 48. Said devices comprise a sleeve 50 formed with a central opening through which the shank of the pivot screw 47 passes, as shown in Fig. 5. The sleeve 50 is provided with a radial arm 52 which terminates in a diamond-shaped wedge or cam 53. One arm 52 and wedge 53 are preferred but if desired a second may be provided, as indicated in the modified construction shown in Fig. 8 wherein the bearing opening which receives the pivot screw is designated as 51. If preferred additional wedges may be employed. One end of the sleeve 50 is adapted to abut against the cover 49 when the latter is in place. From the opposite end of the 95 sleeve an engaging device, in the form of a pin 54 projects into a slot-way or cut-out 55 formed on the hub 56 of a gear wheel 57 which is shown detached in Fig. 7. The hub and gear wheel are formed with a bearing opening 58 which receives the pivot screw 47. The ends of the cut-away 55 provide shoulders or abutments 55^a and 55^b on the collar 56, which shoulders are adapted to contact with the pin 54. Normally the pin 54 is 100 maintained in contact with the shoulder 55^a by a wire spring 59 coiled around the sleeve 50 and hub 56, these parts having the same diameter and abutting one another so that they form a practically continuous surface 110 except where the cut-out 55 occurs. One end of the spring 59 is hooked in a hole 60 in the gear wheel 57 and the opposite end of said spring is hooked around the radial arm 52. The gear wheel 57 and sleeve 50 are 115 adapted to rotate freely on the pivot screw 47. Because of the tendency of the spring 59 to maintain the pin or engaging device 54 in contact with the shoulder or engaging device 55^a, said gear wheel and said sleeve will 120 turn as a single member unless one of them is held or prevented from movement in which case it may occur that because of the spring connection between the two, the other of them may continue its turning 125 movement, so that a relative movement between the gear wheel and the sleeve may take place. The spring 59, in other words, is double acting. Its operation will be discussed more fully later on. Pins or plugs 61 130

and 62 are adapted to slide loosely in openings 63 formed in the box 48 and cover plate 49 (Fig. 5). These pins, formed with rounded heads 61^a and 62^a are supported on the parallel arms 64 of a checking or retarding spring which is folded as shown at 65 and secured by a headed screw 66 to a block 48^b within and integral with the box 48. The pin 67 (Fig. 4) prevents the checking spring 10 as a whole from turning on the screw 66 as a pivot. An adjusting or thumb screw 68 engages in a threaded opening in one spring arm 64 and is provided with a flange 68^a which contacts with the outer face of the other spring arm 64, the screw passing loosely 15 through the latter arm. The shank of the thumb screw passes through an opening 49^a in the cover plate 49. The head 68^b of said thumb screw is outside the casing where it 20 may be readily manipulated. By turning the thumb screw it will be apparent that the distance between the spring arms 64 may be varied and the rounded heads 61^a and 62^a of the pins 61 and 62 respectively may be 25 brought into varying normal relations, and so that it will require greater or less power to flex the spring checking arms 64. Normally the distance between the contact devices or heads 61^a and 61^b on the checking devices or 30 spring arms is always less than the greatest width of the diamond shaped wedge 53 but in operation the latter is adapted to coöperate with said checking devices and force them apart at times under impulses received 35 from the main carriage propelling spring of the machine, the spring arms 64 yielding as the wedge is passing between them, said spring arms returning to normal position after the wedge has passed them.

40 The gear wheel 57 meshes with a coöperating gear wheel 69 having a hub 70 which receives a pin 71 by which said gear wheel 69 is secured to a shaft 72. Said shaft is adapted to turn in bearing openings in the box 48 and cover plate 49, said box being formed with a thickened portion 48^c to provide a comparatively wide bearing surface for the shaft 72. Said shaft extends forward outside the box 48. This forward portion carries a toothed wheel or pinion 73, the latter being provided with a hub 74 which is suitably secured to the shaft. It will be seen that the toothed wheel 73, shaft 72 and the gear wheel 69 act as a single member and 55 that motion communicated to the toothed wheel 73 will be transmitted by the shaft 72 and gear wheel 69 to the gear wheel 57 and the parts connected therewith. The toothed wheel or pinion 73 underlies the feed rack 11 but normally is separated therefrom. It will be understood that the casing composed of the box 48 and cover plate 49 may serve in effect as a lever of which the screw 47 is the fulcrum and that when the part or arm of 60 said casing at one side of said fulcrum is raised or lowered the other part or arm at the opposite side of said fulcrum will be correspondingly lowered or raised. In the present instance when the casing is mounted in place on the top plate, the hub 74 is fitted 70 into the slot 42^b in the lifting device 42, as shown in Fig. 6. A spring 75, shown in Fig. 3, is coiled around a headed pin 76 on the bracket plate 43 and has one end secured to said bracket plate and the other end underlying the casing of the retarding contrivance. Said spring assists to maintain said retarding contrivance in normal position and to restore it thereto from operating position when the tabulator key is released. 75

80 In operation, when the tabulator key 35 is pressed in, the stop or stops 27 will be swung down into line with the tabulator stop 25 and concurrently the lifting device 42 is raised. This causes the slotted off-set 42^a, 85 acting against the hub 74 to swing the retarder contrivance on its pivot and bring the toothed wheel 73 into engagement with the feed rack 11. Further upward movement of the lifting device 42 will cause the wheel 73 90 to lift the feed rack from the pinion 12, thereby releasing the carriage and permitting the latter to run leftward under the pull of the main spring. This leftward movement of the carriage causes the feed rack 11 to turn 95 the toothed wheel 73 and also the gear wheel 69, both wheels being fixed to the same shaft 72. Rotary movement of the gear wheel 69 will be communicated to the gear wheel 57 and its hub 56. Viewed from the rear as in 100 Fig. 4, the gear wheel 57 and its hub will turn in the direction of the arrow just above said gear wheel in said figure. Suppose that at the time the gear wheel 57 starts to turn, the parts are in the relations shown in Figs. 4 105 and 5 which are corresponding views. In that case, because of their spring connection 59, the sleeve 50 will be turned with the gear wheel 57 and its hub, and the normal relation of these parts will not be altered until the 110 wedge 53 has been brought into contact with the heads of the spring arms 64. When this occurs the spring arms 64 may flex slightly, but these spring arms are much stiffer than the spring 59 so that the spring arms will arrest the wedge 53 and the sleeve 50 on which it is mounted. Notwithstanding the arrest of the sleeve 50, the hub 56 and the gear wheel 57 will continue to turn by reason of the lost motion connection between these 115 two parts and the sleeve 50, which lost motion connection permits relative rotary movement between the gear wheel 57 and its hub on the one hand and the sleeve 50 and wedge 53 on the other hand. During 120 this relative rotary movement the spring 59 will of course be wound up beyond its normal tension. As soon as the hub 56 begins to turn independently of the sleeve 50 the shoulder 55^a will separate from the pin 54 on the 125 130

sleeve and the shoulder 55^b will approach the opposite side of said pin 54. When the shoulder 55^b engages the pin 54, the sleeve 50 and wedge 53 will be forced ahead and 5 the wedge will press the spring arms 64 apart so that said wedge may pass between them. As soon as this occurs the spring 59 will at once advance the sleeve 50 relatively to the hub 56 until the pin 54 is brought into contact again with the shoulder 55^a. Thereafter if the run of the carriage continues, the operation above outlined will be repeated; that is, the sleeve 50 and gear wheel 57 will turn together until the wedge 53 again contacts with the spring checks 64 which devices will snap back to normal position as soon as the wedge 53 has passed them in the course of the operation above described. When the wedge 53 has again engaged the spring 20 arms 64 said wedge and the sleeve 50 will again be arrested and the train of devices comprising the gear wheels 57 and 69 and the pinion 73 will turn independently until the shoulder 55^b contacts with the pin 54 and 25 forces the wedge 53 past the stationary checking devices. When the run of the carriage has ended by the contacting of the stop 25 with a stop 27, the tabulator key 35 may be released and the parts will thereupon be 30 restored to normal position. The retarding contrivance will be restored by the combined operation of the lifting device 42 and its connected parts and of the restoring spring 75. It will be apparent that my improved retarding contrivance insures that a free movement of the carriage, when first released after the retarding contrivance has been connected with it, shall always take place. The extent 35 of this free initial movement may vary because sometimes at the start the wedge 53 may be farther from the stationary checking devices than at other times, and this free initial movement will in such case be made up of the distance the wedge has to travel 40 before being arrested by the stationary checking devices plus the distance the gear wheel 57 may travel thereafter independently of the wedge 53 and sleeve 50 before engagement of the shoulder 55^b with the pin 54. It may happen that at the time the carriage 45 starts to run, the wedge 53 may be engaged with the stationary checking devices or spring arms 64 in which case the initial free run of the carriage will correspond with the distance the gear wheel 57 will turn before the shoulder 55^b engages with the pin 54. The parts are so proportioned, however, 50 that this distance is sufficient to permit the carriage to acquire considerable momentum before the retarding contrivance is brought into active operation, such distance, for example, as twenty or more letter spaces. The initial free run of the carriage will never be less than the distance corresponding to that 55 of the independent turning movement of the

gear wheel 57, as will be apparent from a study of the construction. Suppose that the wedge 53 be arrested by the stationary checking devices and that the independent turning movement of the gear wheel 57 has begun, causing the separation of the shoulder 55^a from the pin 54 and that at this time the carriage be arrested and the tabulator key be released; thereupon the spring 59 will unwind until the shoulder 55^a has been moved back into contact with the pin 54. During this backward movement of the shoulder 55^a it will be noted that the gear wheel 57 will turn backward, thereby causing backward turning movement of the gear 80 wheel 69 and of the pin 73. Further it will be noted that the end of the spring 59 which is hooked around the arm 52 of the wedge 53 will remain stationary while the other end of the spring 59, which is secured on the gear wheel 57, will move.

Each time that the wedge 53 is forced past the stationary checking devices the carriage will be momentarily checked or retarded and its momentum will be somewhat lessened. As thereafter the momentum is again on the increase the checking devices will again come into operation, tackling the carriage so to speak and repeating the momentary retardation of the carriage. The 95 result is that after the first initial free movement of the carriage said carriage will be subjected, if the run continues long enough to periodic tackling or retardation which may be so regulated both in extent and in the 100 interval between recurrent operations that harmful shock of the arresting parts may be avoided and without causing an unnecessary loss of time such as may occur with other forms of retarding contrivances. Furthermore, during short runs of the carriage when harmful shock to the arresting parts does not occur, the retarding devices may not be brought into play at all, by reason of the lost motion connection which operates initially when the carriage is released. Owing to the fact that the only part, viz., the wedge 53, which coacts or can directly with the stationary checking devices, has a lost motion or a spring connection with the carriage 110 when the latter is running independently of its escapement mechanism, a free initial movement of the carriage when released from said escapement mechanism is always certain to occur.

Various changes may be made without departing from the spirit of my present invention. For example, instead of employing the thumb screw 68 for regulating the tension of and relation between the spring arms 64, said thumb screw 68 may be dispensed with and a regulating device like that illustrated in Figs. 9 to 11 may be used. As shown in these figures a longitudinal slot 48^y may be formed in the upper or top face of the box or 120

container 48. Fitting into this slot is the neck 77 of a slidable regulating device which further comprises a transverse body portion 78 within the box, said body portion having two downwardly extending fingers 78^a which contact with the outer faces of the spring arms 64^a, said spring arms being always embraced between the fingers 78^a. As best shown in Fig. 11, the spring arms 64^a are separate pieces, being secured one at each side of a block 48^x integral with the box 48 by a headed screw 79. The upper face of the neck 77 is formed with a tapped opening which receives a thumb screw 80, the flange 80^a whereof is adapted to engage the top face of the box 48. The construction is such that when the thumb screw is tightened it draws together the flange 80^a and the upper face of the body 78, binding the box 48 between these two parts at either side of the neck 77. When the thumb screw is loosened, the tension regulating device 78 may be slid lengthwise of the slot 48^y to the desired position and thereafter secured in said position by tightening the thumb screw. It will be apparent that as the regulating device 78 is moved toward the devices 64^b at the free ends of the stationary checking devices or spring arms 64^a the length of said spring arms will be shortened so that it requires greater expenditure of energy to force them apart. In other words, the retarding effect may be regulated by adjusting the device 77 along the slot-way 48^y. When this device is employed, the spring arms 64^a are always maintained parallel no matter in what position the device 78 is adjusted. It is of course to be understood, however, that any other suitable regulating device for the checking or resisting device may be made use of within my invention; that the checking device itself may be altered in construction and arrangement; that the pins 61 and 62 may be omitted but the heads 61^a and 62^a preferably retained and that various other changes may be made in other parts of the retarding contrivance in order to adapt it to other conditions and for improving its construction.

In Figs. 12 to 14 of the drawings I have illustrated other means for connecting the retarder with the carriage and for releasing said carriage. In the construction first described, the retarder is connected with the carriage through the usual swinging carriage feed rack by a pinion 73, which pinion also serves to swing said carriage feed rack on its pivots so as to release the carriage. In order to reduce wear on the teeth of said carriage feed rack and to reduce the liability of breakage of said teeth by reason of the co-action of the pinion 73, I prefer to provide a separate rack for co-operation with the retarder pinion, which rack is in the present instance fixed to the carriage and serves to connect

said carriage with the retarder; and to provide other means acting on the usual carriage feed rack to swing it away from the carriage feed pinion and thus release the carriage. The additional rack 81 is fixedly secured near its ends by screws 82 to lugs 6^a projecting rearward from the upper part of the carriage slide bar 6. The rack 81 is arranged in rear of the feed rack 11 and on a level therewith as best shown in Fig. 12. The retarder contrivance is so constructed and mounted on the top plate that the pinion 73 underlies the rack 81 instead of the rack 11 as in the former construction. The slotted extension 42^a of the lifting device 42 engages with the forward end portion of the shaft 72, which in this instance projects forward beyond the pinion 73 as shown in Fig. 14. When the lifter 42 is raised by operating the tabulator key 35, the retarder contrivance will be swung on its pivot to bring the pinion 72 into mesh with the rack 81. The carriage is released at this same operation by a lever 83. Said lever is provided with a hub 84 which receives a shoudered screw 85 that engages in a tapped hole in the lower guide rail 8 and provides a fulcrum for the lever 83. Said lever curves downward, leftward and upward from its fulcrum and is also off-set forward slightly, terminating in a rounded lifting shoe 86 which underlies the feed rack 11. A pin 87 fixed to and projecting forward from the lifter 42, engages in a slot 88 in the lever 83, this loose connection permitting the lifter 42 to swing the lever 83 upward, causing the shoe 86 to engage the feed rack 11 and separate the latter from the feed pinion 12. The parts are so timed that when the lifting shoe 86 contacts with the teeth of the rack 11, the pinion 73 will already have entered for a short distance the teeth of the rack 81, thus insuring a connection of the retarder with the carriage before the release of said carriage shall have begun. When the carriage is finally released the pinion 73 will be fully engaged with the rack 81. As stated, I prefer to connect the retarder and release the carriage by the means shown in Figs. 12 to 14; but the first described or any other construction may be employed in connection with my retarder contrivance, and said contrivance itself may be altered in various respects without departing from my invention.

It will be noted that by my present invention I provide a checking device (the wedge shaped cam 53 in the present instance) which has a yielding connection through the spring 59 with the carriage of the machine, said carriage operating to move or rotate said checking device; that a co-acting checking device or devices (that is, the spring arms) is provided with which the movable checking device is contactive in the operation of the retarder contrivance; that no part movable by

the carriage is contactive with said co-acting checking device except said movable checking device; that, owing to the fact that this movable checking device is yieldingly connected to the carriage by a spring or yielding connection which provides for a lost motion, a preliminary free run of the carriage is insured prior to the effective operation of the retarder; that the co-acting checking devices are mounted on a support which remains stationary during the run of the carriage; that harmful vibration of the co-acting checking devices or noise due to vibration is prevented, the preventing means in this instance being the slideable pins 61 and 62; that there is a part or cam 53 which is movable by the carriage into the path in which both the co-acting checking devices normally lie; that the hub or part 56 is movable by the carriage; that the sleeve or second part 50 is mounted independently of the first part 56; that a yielding connection comprising the spring 59 joins said parts 56 and 50; that said yielding or spring connection transmits rotary movement from one to the other of said parts; that one of said parts or rotary devices (50 in the present instance) carries a cam fixed thereon, said cam being yieldingly connected with the carriage through the yielding or spring connection 59; that said yielding connection tends to maintain the parts 56 and 50 in a normal relationship; that in said normal relationship the co-acting engaging devices 55^a and 54 on said parts are in contact; that the checking or retarding devices 64 are engageable by the cam 53 on the part 50 to hold the engaging part 50 until other of said engaging devices (that is, 55^b and 54) are brought into co-action; and that the engaging devices may be considered to be first the shoulder 55^a and the side of the pin 54 contiguous to said shoulder 55^a, and, second, the shoulder 55^b and the side of the pin 54 which is adapted to contact with said shoulder 55^b.

What I claim as new and desire to secure by Letters Patent, is:—

1. In a retarder contrivance for type-writing machines, the combination of a checking device, a yielding connection between said checking device and the carriage of the machine which connection operates to move the checking device independently of the retarding action, and a co-acting checking device, the movable checking device being the only part connected to the carriage which can contact with said co-acting checking device.

2. In a retarder contrivance for type-writing machines, the combination of a checking device mounted on a support which remains stationary during the run of the carriage, a part movable by the carriage in a path in which said checking device normally lies, and a yielding connection between said

part and said carriage, through which motion is transmitted independently of the retarding action, said checking device being contactive only with said part.

3. In a retarder contrivance for type-writing machines, the combination of a part movable by the carriage of the machine, a second part mounted independently of the first part, a yielding connection between said parts which transmits motion from one part to the other independently of the retarding action, and a checking device with which said second part co-acts.

4. In a retarder contrivance for type-writing machines, the combination of a part rotatable by the carriage, a second part mounted independently of the first part, a spring connecting said parts to transmit rotary movement from one to the other independently of the retarding action, and a checking device with which said second part co-acts.

5. In a retarder contrivance for type-writing machines, the combination of a cam, a yielding connection between said cam and the carriage of the machine, and a spring checking device co-operative with said cam.

6. In a retarder contrivance for type-writing machines, the combination of a rotary device, a cam fixed thereon, a yielding connection between said device and the carriage of the machine, and a yieldingly mounted checking device co-operative with said cam.

7. In a retarder contrivance for type-writing machines, the combination of a rotary sleeve, a cam fixed thereon, a mechanical lost motion connection between said sleeve and the carriage of the machine, and a checking device movable by said cam.

8. In a retarder contrivance for type-writing machines, the combination of a part movable by the carriage of the machine, a second part mounted independently of the first part, a spring connecting said parts and transmitting motion from one part to the other, said spring tending to maintain them in normal relationship, and a checking device with which said second part co-acts.

9. In a retarder contrivance for type-writing machines, the combination of a part movable by the carriage, a second part mounted independently of the first part, co-acting engaging devices on said parts, a yielding connection between said parts which transmits motion from one part to the other, and a checking device with which one of said parts co-acts.

10. In a retarder contrivance for type-writing machines, the combination of a part rotatable by the carriage, a second rotary part mounted independently of the first part, co-acting engaging devices on said parts, a spring connecting said parts and tending to maintain certain of said engaging devices in

engagement, said spring transmitting motion from one part to the other, and a checking device engageable by one of said parts.

11. In a retarder contrivance for typewriting machines, the combination of a part rotatable by the carriage, a second rotary part mounted independently of the first part, co-acting engaging devices on said parts, a spring connecting said parts and tending to maintain certain of said engaging devices in engagement, and a checking device engageable by one of said parts and operative to hold said engaging part until other of said engaging devices are brought into co-action.

12. A retarder contrivance for typewriting machines comprising in combination a gear wheel having a hub provided with engaging devices, a sleeve provided with engaging devices coöperative with engaging devices on said hub, a spring connecting said hub with said sleeve, a cam on said sleeve, and a checking device coöperative with said cam.

13. A retarder contrivance for typewriting machines comprising in combination a gear wheel having a hub provided with engaging devices, a sleeve provided with engaging devices coöperative with said engaging devices on said hub, a spring connecting said hub with said sleeve, a cam on said sleeve, and two yielding checking devices adapted to be forced apart by said cam.

14. A retarder contrivance for typewriting machines comprising in combination a gear wheel having a hub formed with a cut-out portion, a sleeve having a pin projecting into said cut-out portion, a coiled spring connecting said hub and said sleeve, said spring operating to maintain said pin normally in contact with one end of said cut-out portion, a cam on said sleeve, and a yielding checking device coöperative with said cam.

15. A retarder contrivance for typewriting machines comprising in combination a gear wheel having a hub formed with a cut-out portion, a sleeve having a pin projecting into said cut-out portion, a coiled spring connecting said hub and said sleeve, said spring operating to maintain said pin in contact with one end of said cut-out portion, a wedge-shaped cam on said sleeve, and a pair of yielding checking devices adapted to be forced apart by said wedge-shaped cam.

16. A retarder contrivance for typewriting machines comprising in combination a gear wheel having a hub formed with a cut-out portion, a sleeve having a pin projecting into said cut-out portion, a coiled spring connecting said hub and said sleeve, said spring operating to maintain said pin in contact with one end of said cut-out portion, a cam on said sleeve, parallel spring arms, and pins carried by said arms.

17. A retarder contrivance for typewriting

machines comprising in combination a gear wheel having a hub formed with a cut-out portion, a sleeve having a pin projecting into said cut-out portion, a coiled spring connecting said hub and said sleeve, said spring operating to maintain said pin in contact with one end of said cut-out portion, a wedge-shaped cam on said sleeve, parallel spring arms, devices on said arms coöperative with said cam, and a device for regulating the tension of said spring arms.

18. In a typewriting machine, the combination with a carriage having a rack thereon, of a retarder contrivance comprising a key-controlled casing pivoted on the frame of the machine, a toothed wheel outside the casing and engageable with said rack, a rotary part provided with engaging devices, gearing connecting said rotary part with said toothed wheel, a second rotary part provided with engaging devices and carrying a checking device, a spring connecting said rotary parts, and a spring checking device coöperative with said first recited checking device.

19. In a typewriting machine, the combination with a carriage having a rack thereon, of a retarder contrivance comprising a key-controlled casing pivoted on the frame of the machine, a toothed wheel outside the casing and engageable with said rack, two relatively movable engageable rotary parts, gears connecting one of said rotary parts with said toothed wheel, a cam on the other rotary part, and a yielding check coöperative with said cam.

20. In a typewriting machine, the combination with a carriage having a rack thereon, of a retarder contrivance comprising a key-controlled casing pivoted on the frame of the machine, a toothed wheel outside the casing and engageable with said rack, a gear having a fixed relation with said toothed wheel, an intermeshing gear having a hub formed with a cut-out, a sleeve having a pin entering said cut-out, a coiled spring connecting said sleeve with the hub and maintaining said pin normally in contact with one end of said cut-out, a cam on said sleeve, and a spring check coöperative with said cam.

21. In a typewriting machine, the combination with a carriage having a rack thereon, of a retarder contrivance comprising a key-controlled casing pivoted on the frame of the machine, a toothed wheel outside the casing and engageable with said rack, a gear having a fixed relation with said toothed wheel, an intermeshing gear having a hub formed with a cut-out, a sleeve having a pin entering said cut-out, a coiled spring connecting said sleeve and said hub and maintaining said pin normally in contact with one end of said cut-out, a cam on said sleeve, a spring checking device coöperative with said cam, and means

for regulating the resistance of said checking device.

22. In a typewriting machine provided with a carriage and carriage feeding devices including two co-acting separable parts, the combination of a rack on said carriage and independent of said carriage feeding devices, a retarder mechanism comprising a movable element carrying a toothed wheel engageable with said rack, a lifting device for moving said element and causing said toothed wheel to engage said rack, and a member operatively connected with said lifting device for separating said separable parts of the carriage feeding devices.

23. In a typewriting machine provided with a carriage and carriage feeding devices including two co-acting separable parts, the combination of a rack fixed to said carriage and independent of said carriage feeding devices, a retarder mechanism comprising a casing pivoted on the frame of the machine, a toothed wheel outside the casing and co-operative with said fixed rack but normally separated therefrom, a key-controlled slideable lifting device operative to swing said casing on its pivot and bring said toothed wheel into engagement with said fixed rack, and a lever operative by said lifting device to separate said separable parts of the carriage feeding mechanism.

24. In a typewriting machine provided with a carriage and carriage feeding devices including a pinion and a swinging rack normally engaging said pinion, the combination of a rack fixed on said carriage, a retarder mechanism comprising a pinion engageable with said fixed rack and mounted on a shaft connected with the retarder devices proper, a key controlled lifting device engaging said shaft, and a lever pivoted on a fixed part and operative by said lifting device to swing said swinging rack out of engagement with its pinion.

25. In a typewriting machine provided with a carriage and carriage feeding devices including a pinion and a swinging rack normally engaging said pinion, the combination of a rack fixed on said carriage, a retarder mechanism comprising a pinion engageable with said fixed rack and mounted on a shaft connected with the retarder devices proper,

a key controlled lifting device engaging said shaft, and a lever having a pin and slot connection with said lifting device and contactive with said swinging rack to disengage the same from its pinion.

26. In a typewriting machine provided with a carriage and carriage feeding devices including a pinion and a swinging rack normally engaging said pinion, the combination of a rack fixed on said carriage, a retarder mechanism comprising a pinion engageable with said fixed rack and mounted on a shaft connected with the retarder devices proper, a slideable lifting device provided with a slot engageable with said shaft, a key operated mechanism for actuating said lifting device, and a lever having a fixed fulcrum and loosely connected with said lifting device, said lever having a lifting shoe engageable with said swinging rack.

27. In a typewriting machine provided with a carriage and carriage feeding devices including a pinion and a swinging rack normally engaging said pinion, the combination of a rack member on said carriage, a retarder mechanism comprising a toothed wheel engageable with said rack member but normally separated therefrom, a key controlled lifting device for engaging said wheel with said rack member, and a lever operative by said lifting device to disengage said swinging rack.

28. In a typewriting machine, the combination of a carriage carrying two racks, escapement mechanism including a pinion adapted to one of said racks for feeding the carriage step-by-step, a movable retarder adapted to be driven by the other of said racks, a key actuated lifter for moving said retarder into engagement with said driving rack, and a lever connected with said lifter for disengaging said feed rack from said feed pinion.

Signed at the borough of Manhattan, city of New York, in the county of New York, and State of New York, this 20th day of January A. D. 1909.

JACOB FELBEL.
